Inventor:
Oliver Prentiss Smith

By Jones, Addington, Ames & Reithers.

UNITED STATES PATENT OFFICE.

OLIVER PRESTON SMITH, OF CHICAGO, ILLINOIS.

CAP ADAPTER.

Application filed May 9, 1921. Serial No. 468,160.

To all whom it may concern:

Be it known that I, OLIVER PRESTON SMITH, a citizen of the United States, residing at Chicago, in the county of Cook and State of Illinois, have invented new and useful Improvements in Cap Adapters, of which the following is a full, clear, concise, and exact description, reference being had to the accompanying drawing, forming a part of this specification.

This invention relates to a cap adapter, and more particularly to an adapter whereby a large variety of threaded nipples of different sizes and different thread gauges fitted on automobile radiators can be readily standardized to a single and uniform size and thread gauge.

The present trend in the motor world is to substitute fancy and ornate caps for the ordinary and simple cap in almost universal use on radiators heretofore. However, the nipples on the radiators to which these fancy caps must be attached differ in many respects, as for example, the size; gauge of thread, and whether it is threaded within or without, etc. A great saving would consequently be effected and a remarkable convenience attained if a standardized fitting were provided whereby one size of cap could be fitted to and on any and all nipples irrespective of the size and character of the threading of the nipple.

It is one of the objects of this invention, therefore, to provide a cap adapter whereby a standardized size of cap can be secured to any size of radiator nipple of a size somewhat smaller than the size of the cap selected as the standard.

Another object of the invention resides in the production of simple and efficient cap adapters fitted with a self-sealing means between the adapter and the nipple.

Another object resides in the production of a cap adapter which is exceedingly simple in construction and which can be very cheaply manufactured.

Other objects of the invention will become apparent from the accompanying drawings, the following description and the appended claims.

For the purpose of illustration, the preferred form of cap adapter constructed in accordance with the teachings of this inven-

tion is illustrated in the accompanying drawings, in which:

Fig. 1 is a view in side elevation of the adapter fitted on the radiator nipple;

Fig. 2 is a longitudinal section through the nipple and cap adapter;

Fig. 3 is a longitudinal section taken at right angles to the section shown in Fig. 2, and illustrates in detail the manner of attaching the adapter to the radiator nipple;

Fig. 4 is a bottom view of the cap adapter; and,

Fig. 5 is a plan view of the adapter.

Figure 6 is a detailed view of one of the plates comprising the mechanism for retaining the cap adapter in position.

As illustrated in Figs. 1 to 3, inclusive, the cap adapter 8 is secured to the usual nipple 9 attached to the radiator casing 10. The adapter comprises an annulus or disk 11 which is preferably inclined at a slight angle from the horizontal, as clearly illustrated in Fig. 2. Secured to and depending from this disk 11 is a flange 12 on one side thereof and a flange 13 on the other side thereof. The flange 12 is fitted with the threads 14 to which the cap is secured. The flange 13 has secured thereto the ears 15 and 16 extending at right angles to the flange 13.

Positioned under the disk or annulus 11 is a gasket 17. This gasket can be made of any suitable material, but is preferably constructed of a soft metal such as lead. The gasket 17 serves to seal the connection between the upper edge 18 of the radiator nipple and the annulus 11 of the cap adapter 8. This sealing is effected by drawing the annulus down into position on the edge 18, which results in a sliding action between the edge 18 of the radiator nipple and the gasket 17, and this results in a permanent seal at the interconnection.

Any suitable means can be utilized for permanently positioning and securing the cap on the radiator nipple 9. In the preferred form shown in the drawings, this is effected by a toggle bolt construction clearly illustrated in Figs. 2, 3 and 4. The toggle bolt mechanism utilized to hold the cap in its position consists of the bolts 20 and 21 which are threaded through perforations in the ears 15 and 16, respectively. Each of these bolts is fitted with plates such as 22

and 23, respectively, which are pivoted at their inner ends on pins such as 24 and 25, respectively. The pin 25 is equipped with a spiral spring such as 26 which serves to hold the plates 22 and 23 in their extended substantially horizontal position, as illustrated in Figs. 3 and 4. Secured to the plates 22 and 23 is a disk such as 28 which receives the bolts 20 and 21, and thereby secures these plates and their associated apparatus to said bolts. Interconnecting the plates 22 is the metallic strap 30, and a similar strap interconnects the plates 23.

From the construction illustrated in Figs. 3 and 4, it will be evident that the plates 22 and 23 can be moved upwardly about the pivots 24 and 25 against the action of the spring 26. Due to this movement the width of the metallic straps 30 and 31, secured to the plates 22 and 23, can be materially reduced and this will permit the introduction of the plates 22 and 23 and the associated metallic straps 30 and 31 into the nipple opening 32. When the mechanism is thus introduced into the nipple opening 32 and slid down into position, so that the plates 22 and 23 and the straps 30 and 31 drop below the lower plane of the nipple opening, they will expand, due to the action of the spring 26, and assume a position as shown in Fig. 3; whereby the straps 30 and 31, when the bolts 20 and 21 are drawn tight, will contact with and be drawn up against the radiator casing 10.

Upon expanding the plates 22 and 23, the edges 35 thereof are brought against the sides of the bolts 20 and 21, as indicated at 36 in Fig. 3. Consequently further movement of these plates will be prevented, so that collapsing of the plates 22 and 23 in a downward direction is impossible.

It will now be evident that the construction illustrated and hereinbefore described can be inserted and secured to any size of radiator nipple, since, by collapsing the metallic straps 30 and 31 and their associated plates, this portion of the cap adapter can be readily slipped into the radiator nipple opening and into position, as illustrated in Fig. 3.

When the metallic straps 30 and 31 are thus positioned, the bolts 20 and 21 are tightened and this will securely clamp the cap adapter on the nipple, the clamping or binding being effected between the edge 18 of the nipple and the gasket 17 and the straps 30 and 31 and the radiator casing 10. It will be evident that as the cap adapter is drawn into position by the interconnection between the metallic straps 30 and 31 and the radiator casing 10, that an automatic sealing will result between the gasket 17 and the upper edge 18 of the radiator nipple. When the cap adapter 8 is thus securely fixed in position in the nipple 9, the outer depending

flange 12 will receive the standard size of fancy or ornate cap which it is desired to substitute for the cap which had been fitted on the threads 34 of the nipple 9. The cap adapter 8 constructed in accordance with the teachings of this invention, therefore, serves to adapt the radiator nipples of sizes somewhat smaller than the size of the standard cap selected, so that the standardized cap can be readily fitted on said nipple by means of said adapter without making any change in the nipple construction and with a minimum amount of effort.

The adapter illustrated in the drawings and described herein, therefore, marks a distinct advance in the use of fancy or ornate caps since it simplifies the stocking problem to the point where the jobber or dealer need carry but one size of cap—the standardized size—instead of keeping in stock caps of different sizes, of different thread gauge, and of different character, depending upon whether they are threaded within or without to fit the large variety of radiator nipples on the market.

Obviously, the invention is not limited to the specific embodiment thereof described herein, but is capable of other applications any many variations as set out in the appended claims.

Having thus described my invention, what I claim as new and desire to secure by Letters Patent is:

1. In a cap adapter, in combination, a disk, flanges depending from each edge of said disk, and means associated and cooperating with one of said flanges to secure said adapter to all standard sizes of radiator nipples, said disk spacing said flanges apart a distance greater than the thickness of the walls of said radiator nipples.

2. In a cap adapter, in combination, an annulus, flanges depending from each edge of said annulus, standardized means associated and cooperating with one of said flanges to secure said adapter to all standard sizes of radiator nipples, and threads on said other flange adapted to receive a standardized radiator cap, said annulus spacing said flanges apart a distance greater than the thickness of the walls of said radiator nipples.

3. In a cap adapter, in combination, a disk, flanges depending from each edge of said disk, standardized means associated and cooperating with one of said flanges to secure said adapter to all standard sizes of radiator nipples, and means cooperating with said disk to seal the interconnection between said nipple and disk, said disk spacing said flanges apart a distance greater than the thickness of the walls of said radiator nipples.

4. In a cap adapter, in combination, an annular disk positioned at an inclination

from the horizontal, a flange depending from said disk, means secured to said flange for attaching said adapter to a radiator nipple, means to bindingly secure the adapter 5 to said nipple, and a gasket associated with said disk which automatically seals the connection between the adapter and the nipple as the adapter is secured in position.

5. In a cap adapter, in combination, an 10 annular disk positioned at an inclination from the horizontal, a flange depending from said disk, means secured to said flange for attaching said adapter to a radiator nipple, a toggle joint mechanism to bind- 15 ily secure the adapter to said nipple, and a gasket associated with said disk which automatically seals the connection between the adapter and the nipple as the adapter is secured in position.

20 6. In a cap adapter, in combination, a cap element adapted to be positioned at the mouth of a radiator nipple, means connected to said cap element and lying below the lower plane of said nipple for securing said 25 cap element in position, said means being collapsible in one direction only for permitting insertion and preventing removal thereof from said nipple, said means being adjustable relative to said cap element whereby

said means may be positioned along its con- 30 nection according to the depth of said nipple.

7. In a device of the class described, a 35 radiator adapter adapted to be positioned at the mouth of a radiator nipple, mechanism for permanently holding said adapter in position, said mechanism including means permitting insertion of said mechanism into 40 said nipple but preventing the removal thereof after inserted.

8. A cap adapter comprising a cap receiving element positioned at the mouth of a radiator nipple said element provided with a standardized thread gauge whereby any 45 of a desired plurality of different ornate caps may be mounted thereon, standardized means cooperating with said element whereby said element may be secured to nipples of different but smaller sizes without requiring a variation in the design or construction of said standardized means, and means carried by said cap receiving element 50 for automatically sealing the connection between the element and the nipple.

In witness whereof, I have hereunto sub- 55 scribed my name.

OLIVER PRESTON SMITH.
